TOY MILKING COW

Martin Shriner, Forest Hills, N. Y., assignor to
Ideal Novelty & Toy Co., Hollis, N. Y., a corpora-
tion of New York

Application May 29, 1948, Serial No. 30,009

4 Claims. (Cl. 46—123)

1

My invention relates to a new and improved toy device in the form of a cow.

It is the principal object of my invention to provide a toy cow which has an internal liquid container, and which can be milked in the same manner as a live cow.

Another object of my invention is the provision of a stuffed toy cow which has a realistic appearance and in which water or other liquid can be stored and dispensed by manipulation of an udder.

A further object of my invention is the provision of a toy cow of the character described which is made of a soft outer material filled with a resilient stuffing which can be used as a bed-toy by children with no sharp or metallic parts exposed.

These and other objects of my invention will be readily apparent in the course of the following specification taken in connection with the accompanying drawings, in which:

Fig. 1 is a side elevation of the toy cow with the center portion thereof and the liquid container shown in section;

Fig. 2 is a side elevation of the liquid container, and its attached udder member; and

Fig. 3 is a top plan view of the liquid container device shown in Fig. 2.

According to my invention, I provide a toy cow, designated generally as reference numeral 10, said toy cow having an outer covering made of plush or other soft material. The said toy cow 10 is filled with a suitable stuffing 11 composed of kapok, cotton, straw or other suitable material. The toy cow 10 has a top wall 12 and a bottom wall 13.

Located vertically within the body of the toy cow 10, a cylindrical tube 14 is provided, said tube being preferably made of aluminum, plastic, or other non-corrosive rigid material. The said tube 14 is open at both its upper and lower ends. Over the top end of the said cylindrical tube 14, a stud shaped filling member 15 is fitted. This filling member is preferably made of latex, although it may be made of plastic or any other bendable and resilient material. The lower end of the filling member is stretched over the upper open end of the cylindrical tube 14, and is frictionally held thereupon. In addition, to further secure the filling member 15 to the cylindrical tube 14, a suitable adhesive may be used if desired. The upper flange 15a of said filling member 15 is provided with a narrow slit 16, the function of which will be presently described.

The open bottom end of the cylinder 14 is

2

covered by a dispensing member 17, said member 17 being made of the same flexible material as the filling member 15. The dispensing member 17 has an upper flange 18 and an udder-shaped lower portion 19, said lower portion 19 being of greater diameter than the cylinder 14. The upper flange 18 stretches over the bottom end of the cylinder 14 and is held thereon by friction. The upper flange 18 of the dispensing member 17 may likewise be secured to cylinder 14 by an adhesive.

The udder-shaped lower portion 19 of dispensing member 17 is provided with a plurality of integral depending nipples 20. Each of said nipples is provided with a minute hole or recess 21 at the bottom edge thereof.

A hole or recess is cut in the bottom wall 13 of the toy cow 10. The upper wall 12 of said toy cow is preferably stitched transversely along the center. The cylinder 14 with its attached filling member 15 and dispensing member 17 is inserted within the body of the toy cow prior to the time that the two halves of the upper wall 12 are stitched together. When inserted, the bottom edge of the cylinder 14 fits snugly within the hole or recess in the bottom wall 13 of the toy cow and is flush with said bottom wall 13. The top wall 12 of the toy cow 10 is then stitched transversely, and around the filling member 15, thus leaving only the upper flange 15a of said filling member protruding from the body of the toy cow. In its inserted position, the udder-shaped lower portion 19 of dispensing member 17 depends from the bottom wall 13 of the toy cow, the upper edge of said dispensing member abutting the outer edge of said bottom wall 13.

The stuffing 11 which reinforces the body of the cow, maintains the cylinder in its upright position, and affords stability thereto.

In use, the liquid container may be filled by inserting the end of an eye-dropper into the slit 16 in the upper flange 15a of the filling member 15. When the eye-dropper is removed, the flexible and resilient character of the filling member 15 causes the slit 16 to close to such an extent that the liquid contained in the cylinder, does not flow from the filling member 15, when the toy cow is inverted. As shown in Fig. 1, the liquid is stored in the udder-shaped lower portion 19 of dispenser 17 and in the cylinder 14. The holes in the bottom of the nipples 20 are of such a small diameter that a liquid with the consistency of milk will be retained in the udder by capillary action without leaking through the said holes. When the liquid is to be dispensed, the udder-shaped member 19 is

grasped and squeezed as shown in Fig. 1, the liquid being forced through the holes 21 in the nipples 20 in streams. It will be noted that the only exposed portions of the device are the flange 15a of the flexible, filling member 15 and the flexible udder portion 19 of the dispensing member 17. The toy cow may therefore be safely used as a bed-toy for infants, without danger of harm to the child through handling of sharp or metallic parts.

While a preferred embodiment of my invention has been shown and described, it is obvious that numerous additions, omissions and substitutions may be made without departing from the spirit and scope thereof.

I claim:

1. In a toy cow having a stuffed body, a liquid dispensing device which extends vertically through said stuffed body, said device comprising a rigid reservoir member, a flexible and resilient filling member attached to and closing off the top end of said reservoir member, and a flexible and resilient udder-shaped dispensing member attached to and closing off the bottom end of said reservoir, said reservoir member being wholly contained within the stuffed body, said filling member and dispensing member protruding respectively from the upper and lower surfaces of said stuffed body, said dispensing member having a hemispherical hollow upper portion, simulating the udder of a cow, said hollow upper portion abutting the bottom surface of the toy cow body and having a plurality of hollow depending nipples containing holes sufficiently small to retain liquid contained in the hollow upper portion until said hollow upper portion is compressed.

2. In a toy cow having a stuffed body, a liquid dispensing device which extends vertically through said stuffed body, said device comprising a rigid reservoir member which is open at both ends, a flexible and resilient filling member attached to and closing off the top end of said reservoir member, and a flexible and resilient udder-shaped dispensing member attached to and closing off the bottom end of said reservoir, said reservoir member being wholly contained within the stuffed body, said filling member and dispensing member protruding respectively from the upper and lower surfaces of said stuffed body, said filling member having a narrow slit in its upper wall which is normally closed, said dispensing member comprising a

hollow hemispherical liquid container which abuts the bottom outer surface of the toy cow body and communicates with said reservoir member, said container having a plurality of hollow nipples, having holes sufficiently small to retain the contained liquid within said container, said container being compressible whereby to force said liquid through the holes in said nipples.

3. In a toy cow having a stuffed body, a liquid dispensing device which extends vertically through said stuffed body, said device comprising a rigid reservoir member which is open at both ends and is completely enclosed within the stuffed body of said toy cow, a flexible and resilient filling member having a lower integral collar which frictionally fits over and closes off the upper end of said reservoir member and an upper, enlarged, flat top-piece which is located adjacent to and abutting the outer top surface of said stuffed body, said top-piece having a planar upper surface containing a narrow slit which is normally closed by the resilience of said top-piece, and a resilient and compressible dispensing member having an integral collar secured to the bottom end of said reservoir member, said dispensing member having a hollow udder-shaped container which depends from the bottom surface of said stuffed body, said udder-shaped container having a plurality of integral depending nipples which contain holes sufficiently small to retain the contained liquid until said udder-shaped container is compressed.

4. A liquid dispensing device according to claim 10, in which the rigid reservoir member is cylindrical, and in which the udder-shaped container has an upper wall of greater diameter than said reservoir member, said upper wall abutting the lower surface of said stuffed body.

MARTIN SHRIER

It is hereby certified that error appears in the printed specification of the above numbered patent requiring correction as follows:

Column 4, line 35, for the claim reference numeral "10" read 3;
and that the said Letters Patent should be read as corrected above, so that the same may conform to the record of the case in the Patent Office.

Signed and sealed this 13th day of March, A. D. 1951.
